UNITED STATES PATENT OFFICE

149,538

DESIGN FOR A HOLDER FOR PLAYING CARDS

Bert J. Bratt, Chicago, Ill.

Application August 22, 1946, Serial No. 132,729

Term of patent 14 years

(Cl. D34—5)

To all whom it may concern:

Be it known that I, Bert J. Bratt, a citizen of the United States, residing at Chicago, in the county of Cook and State of Illinois, have invented a new, original, and ornamental design for Holder for Playing Cards, of which the following is a specification, reference being had to the accompanying drawing, forming a part thereof.

In the drawing:

Figure 2 is a perspective view viewed from the other side of the holder and showing the movable parts in their closed positions.

I claim:

The ornamental design for a holder for playing cards, substantially as shown.

BERT J. BRATT.
